9 Claims. (Cl. 123—61)

ABSTRACT OF THE DISCLOSURE

A reciprocating double acting stepped piston uncovers inlet ports and exhaust ports at each end of its stroke to obtain uniflow scavenging operations. The engine employs a cross head, but the ordinary piston rod and stuffing box have been eliminated. A "cocktail shaker" cooling arrangement is employed in a double acting piston.

The engine described in this invention is particularly suited for medium to large size applications and would be well adapted for large stationary installations and for powering vehicles such as ships and locomotives. The engine shown is a spark ignited gas engine. With modifications, the engine could operate as a diesel engine.

This application is related to my co-pending application Serial Number 479,775 filed Aug. 16, 1965. The engine shown in this present application would have improved fuel economy, reduced maintenance, and longer operating life (but increased initial cost, size, and weight) compared to the engine shown in the co-pending application. Both engines have their field of application.

General advantages of this engine

The engine described herein has the following group of advantages (1 to 8) over conventional engines now in general use. These eight advantages indicate powerful reasons for making progress on this engine and for attacking the problems associated with it.

(1) The engine has two power strokes per rotation of each crank and connecting rod. This permits the engine to have fewer cylinders for a given power output and/or smoother running.

(2) The engine has uniflow type scavenging (instead of cross flow or loop scavenging) and this secures a better flow pattern with less eddy currents, less mixing with exhaust gas, and less short circuiting of the scavenge air.

(3) Not required are power poppet valves, power cams, power cam shafts, power rocker arms, or power push rods.

(4) The wrist pin bearing has bi-directional loading and this permits this bearing to be lubricated by the very reliable "squeeze film process." In a *single acting* two stroke cycle engine, the load on the wrist pin is generally non reversing.

(5) The peak bearing loads are lower because the reciprocating inertia force is cushioned at *each* end of *each* stroke by a gas pressure force.

(6) The exhaust ports can be made shorter in height because they extend around the full periphery of the cylinder instead of part way around as in a cross or loop scavenged engine. Thus the working stroke is longer and B.M.E.P. higher.

(7) The engine is double acting, yet no stuffing box is required.

(8) Because of advantages 1 to 7 above, the engine is more compact, lighter in weight, lower in initial cost, and lower in maintenance when compared with conventional engines now in general use.

Specific objects and advantages of this invention

So as to secure long life and low maintenance, an object is to provide optimum environmental and operating conditions for the working piston 13 and its rings 63. In this

2

regard, the working piston has no con rod side thrust imposed on it since this is borne by the crosshead 6. The absence of con rod side thrust on the working piston reduces its lubrication requirements with a saving of wear and lube oil.

An advantage is that the con rod is not located within the front valve piston 14 and therefore the diameter of piston 14 is determined primarily by the requirement to secure adequate flow area for the inlet ports 18. This permits the diameters of the valve pistons 14 and 15 to be reduced with a consequent reduction in the diameter of the working piston 13 for a given displacement of the engine. This in turn secures two advantages: (1) there is less surface area exposed to combustion for a given displacement and (2) there is a smaller circumference to seal for a given displacement.

The valve pistons 14 and 15 must be sealed to prevent leakage of gas. An object of this invention is to employ expanding type seal rings 26 on the valve pistons instead of using non reciprocating contracting type seal rings in the valve cylinders. The advantages of this are explained in subsequent paragraphs (a) to (d).

Another object is to provide means for imparting a rotational motion or swirl velocity to the air inside the chambers so as to improve scavenging, fuel-air mixing, and combustion.

Another advantage is that the engine is less subject to thermal distortion. The cylinders are concentric about their axes and so are the pistons which are devoid of wrist pin bosses or holes. Also, the gas flow and the combustion process is concentric about the cylinder axis. Therefore, the thermal expansion of these components will be concentric so as to avoid out of round distortion. Less distortion may secure less blow by, less oil consumption, and less chance of seizure. The above is in contradiction to non concentric engines such as loop scavenged engines in which air cooled inlet ports and hot exhaust ports are located on opposite sides of the cylinder.

Another object is to provide a simple effective method for internally cooling the working piston 13 and its two valve pistons 14 and 15.

Another object is to make the piston assembly a one piece casting which is easy to cast. The interior of the piston assembly is liquid cooled, yet there is no need to form a tortuous path for the flow of liquid coolant. The ends of the casting are open for core support. These features simplify the casting job.

Another object is to prevent (as much as practicable) the inlet scavenging air from being heated prior to its entrance into the working chambers 23 and 24. This will increase power output, reduce detonation, and probably secure a slight improvement in fuel economy.

Another object is to secure low flow resistance for the flow of scavenging air on its way to the front inlet ports 18. Low flow resistance aids the scavenging process and reduces scavenge pump power consumption.

Another object is to provide an engine which is double acting and which is relatively compact in overall height even though it employs a crosshead and a crosshead guide.

Another object is to couple the piston assembly to the crosshead 6 in such a manner that the cast piston assembly is always located principally in compression. Thus undesirable tension loads and stress concentrations in these cast parts are eliminated or reduced to a minimum.

Another object is to provide an engine in which each working cylinder is double acting and has only a single exhaust connection. This reduces the amount of exhaust manifolding required and simplifies the engine in general.

Another object is to provide an engine which is double acting, two stroke cycle, and also V type. This permits the engine to be remarkably powerful for a given overall size. The V arrangement permits some components

to perform double duty hence a saving in cost and weight. The inlet manifolding is simplified. The single exhaust manifold 67 serves two banks of double acting cylinders and this results in a very simple exhaust system for such a powerful engine.

Another object is to let the frame top 4 serve a two-fold purpose; i.e. (1) it serves as a frame stop and (2) it serves as a crosshead guide. This simplifies construction and reduces cost.

Another object is to incorporate an inlet air manifold 38 in the frame top and thereby save the cost of a separate manifold and improve the appearance of the engine.

Another object is to let the flanged and bolted joint 41 serve a double purpose as will subsequently be explained.

Brief description of the drawings

FIG. I is a sectional view (taken perpendicular to the crankshaft) of a V engine. Some of the engine parts on the right hand side of the drawing have been omitted because of lack of space on the sheet. A separate scavenge pump is shown schematically at 36 with arrowed lines 37, 65, and 66, indicating conduit connections to 3 separate air manifolds.

FIG. II is a larger scale section view of the mid-portion of the engine shown in FIG. I. The view is taken through the axis of the wrist pin 7 in a plane 90 degrees to that of FIG. I.

FIG. III is a larger scale section view of the top portion of the engine shown in FIG. I. The view is taken in the same plane as FIG. II.

FIG. IV is a partial section view of the sleeve 28 and the view is taken through the inlet ports 18.

FIG. V is an elevation view of the swirl vane assembly 31.

General description and operation

Throughout the description and claims, the front of the engine is defined as being nearer the crankshaft than the back.

A crankshaft 1 having multiple crankpins 2 is journaled in the main frame or crankcase 3. The frame top structure 4 is bolted rigidly to the main frame and is provided with cylindrical bores 5 which serve as crosshead guides. The crossheads 6 reciprocate in the bores 5 and are connected to the crankpin by means of the wrist pins 7 and connecting rods 8. The working cylinder 9, front cylinder head 10, and a back cylinder head 11 are all mounted to the frame top with a set of long steel tension rods 12. The double acting working piston 13, front valve piston 14, and back valve piston 15 form a reciprocating piston assembly or unit. The valve pistons reciprocate in bores in their respective cylinder heads. The piston assembly is fastened to the crosshead by means of the hollow steel rod 20. The cylinder and heads have liquid coolant passages 21. The two combustion chambers 25 and 32 are each provided with at least one fuel gas valve 34 and spark plug 35. The words "LUBE OIL" are shown in FIG. I to indicate a means for lubricating the crankshaft, connecting rods, and crossheads and to illustrate the presence of oil spray inside the crankcase. The exhaust manifold 67 serves two banks of double acting cylinders.

When near top dead center stroke position, the working piston 13 uncovers the exhaust ports 22 and the front valve piston 14 uncovers the front inlet ports 18 so as to obtain a uniflow type scavenging operation of the front working chamber 23. When the pistons are near bottom dead center, scavenging air is supplied through the back inlet ports 19 and the back working chamber 24 is uniflow scavenged exhausting through the same ports.

Discussion of valve piston seal rings

In order for the engine to be successful, it is necessary to provide seal rings for the valve pistons 14 and

15. It is advantageous that expanding rings 26 be placed on the valve pistons and reciprocate therewith instead of employing nonreciprocating contracting rings mounted in the cylinder head. This is explained in the following paragraphs (a) to (d):

(a) At the time of peak pressure and temperature in the back combustion chamber 25, the seal ring 26 (FIG. III) is shielded by distance B. In order for the hot combustion gases to reach ring 26, the gas must travel distance B in the narrow dead end clearance space 27 between sleeve 17 and piston 15. The gases will be substantially reduced in temperature upon reaching the ring 26 due to the long narrow path B and the cooling effect of the water cooled head 11 and oil cooled piston 15.

10 (b) If contracting rings were located in the head, they would not have the benefit of the distance B effect described above and instead would be always directly adjacent the hot combustion chamber 25.

15 (c) An external ring groove in piston 15 is much easier to machine and inspect than would be an internal ring groove inside the head 11.

(d) A one piece contracting ring would be difficult to snap into an internal ring groove unless the groove were formed of separable pieces. (Too complex.)

20 (e) It is not necessary to make the piston 15 of a wear resisting material as the seal ring 26 rides with the piston and not against it.

The sleeve 28 projects into the front combustion chamber 32 and the front inlet ports 18 pass through its wall. 25 The sleeve 28 and the liner portion 16 are the same piece of metal. The purpose of the sleeve 28 is to retain the seal rings 26 so that they do not snap out of their grooves. The sleeve-liner 16 has a further function which is described in the discussion of the crosshead.

Discussion of scavenge air supply system

An object is to prevent (as much as practicable) the inlet scavenging air from being heated prior to its entrance into the working chambers so as to increase 40 the power output and reduce detonation. Therefore, the inlet air is not conducted through the center of the piston assembly but is instead introduced at each end. Concurrently, the pistons are internally cooled by means of liquid coolant instead of being cooled with the scavenging air.

45 Referring to FIG. I, scavenge air (from any suitable scavenge pump 36) is conducted 37 to the manifold passage 38 cast in the frame top 4. The front head 10 has an off center passage 39 for the purpose of conducting the inlet air to the back end of the bore 5. The air makes a 180 degree turn at 29 (FIG. II) around the front end of sleeve 16, flows past the swirl vanes 30, and then flows through the front inlet ports 18. Air for the back working chamber 24 is supplied from a separate manifold 40.

50 55 The bolted joint 41 serves a double purpose; i.e. (1) It fastens the front head 10 to the frame top 4 and (2) It conducts inlet air at 39 so as to save a separate bolted connection.

60 Swirl vanes 30 and 31 are mounted on the piston rod upstream from each set of inlet ports 18 and 19. The vanes have a spiral contour and thereby impart a swirl velocity to the inlet air *prior* to passage of the air through the inlet ports. An additional aid in obtaining swirl is to also slope the inlet ports as shown in FIG. IV.

Internal cooling of pistons

65 The pistons are cooled by a modified "cocktail shaker" principle. This general principle is common practice in single acting engines but is probably novel in the manner in which it is employed in this double acting engine.

70 75 Lube oil is supplied under pressure to the crankpin and up the drilled con rod 8 (FIG. III). The oil lubricates the wrist pin bearing 42; passes through holes 43; passes along the interior of the wrist pin 7; and then

passes through holes 44, 45, and 46 to the inside of the tube 47 which is located inside the hollow steel piston rod 20. The oil then flows to the end of the tube (FIG. III) and then flows through radial holes 48 to the hollow interior 49 of the back valve piston. Oil is allowed to partially fill the hollow spaces 49, 50, and 51 inside the piston assembly. Reciprocating piston motion and inertia of the oil causes the oil to be thrown back and forth inside the hollow interior thus cooling the pistons. As the pistons approach bottom dead center stroke position, the oil is thrown into the front section 51 (FIG. II) where a static oil pressure is momentarily built up due to the acceleration and the height of the oil column inside the section 51. This momentary static pressure forces oil through drilled holes 52 into the hollow steel rod 20 where the oil then empties down into the frame 3. Near top dead center a similar action occurs in which the oil flows through holes 53 (FIG. III) into the hollow steel rod 20 and this oil then empties into the frame on the next downstroke. The rate of oil flow up the con rod and into the piston assembly can be set approximately constant according to the size of the holes 44, 45, and 46 and the supply pressure. When the hollow space 49, 50 and 51 begins to fill with more oil, the cyclic oil pressure increases due to higher columns of oil inside the pistons. More oil pressure causes the oil to drain faster through the holes 52 and 53. It is thus seen that the system is self regulating. That is, the pistons neither become too full of oil nor do they become starved for cooling oil. There is always a proportion of oil and air inside the piston assembly. Air alternately re-enters the hollow space 49, 50, and 51 also through the holes 52 and 53.

The center baffle 54 causes oil to splash against the inside walls of the working piston 13 (cooling same) and also prevents the oil from being thrown from one end of the piston assembly clear to the other end with a consequent oil hammer effect.

This particular type of oil cooling system for the piston assembly has several advantages which are: (1) The oil is well distributed to all parts of the assembly, (2) The heat transfer rate is greatly improved due to the violent shaking action, and (3) It is not necessary to guide the oil along a tortuous path with many small passages in order to assure good distribution of the coolant. Therefore the piston assembly can be a simple one piece casting.

Discussion of pistons and piston rod

The working piston 13 and the two valve pistons 14 and 15 are cast as an integral unit for rigidity, alignment, and reduced cost. With "cocktail shaker" type cooling, the interior of the piston assembly need not be complex in shape and this aids the casting job. The hollow interior of the casting is open at both ends for core support when pouring the casting. The open ends are closed (at assembly) by the piston rod 20 and disc 55 which clamp the casting tightly in compression. The working piston 13 has a series of radial ribs 68, cast inside of it. When a power stroke occurs in the front combustion chamber 23, there is a gas pressure force against the front face 57 of the working piston. This force is transmitted as a compression load through the ribs 68 to the back valve piston 15. The back valve piston in turn is loaded in compression and transmits the force to the disc 55 and steel rod 20. The steel rod is then loaded in tension as it pulls on the crosshead 6. When a power stroke occurs in the back combustion chamber 24, the cast piston assembly is still loaded in compression in a similar manner. It is thus seen that by coupling the piston assembly to the crosshead as shown (clamped at both ends with a steel rod) the casting is subjected essentially to compression loading and undesirable tensile stresses are avoided. It is well known that most cast irons are weak in tension but very strong in compression.

The construction shown has the further advantage that stress concentration at the corner juncture 56 is avoided.

If the front valve piston 14 were attached directly to the crosshead 6 (instead of using the piston rod construction shown) then the front valve piston 14 would be loaded alternately in tension and compression. The tension load 5 would have to be transmitted around the corner 56 (to the face 57 of the working piston) causing an undesirable stress concentration at the corner 56.

It is desirable that the scavenging air have a free unrestricted flow path so as to prevent air pressure drops. Referring to FIG. II, the piston rod 20 does not interfere with the flow of scavenge air (on its way to the front inlet ports 18) since there is a large annular flow path 58 between the sleeve 16 and the piston rod 20. The rod is curved at 59 to give a streamlining effect for 15 the flow of scavenge air.

In summary then, the piston rod 20 secures the following functions and advantages: (1) It couples the piston assembly to the crosshead with minimum tensile rod stresses and stress concentrations in the cast piston assembly, (2) The rod permits unrestricted flow for the scavenge air on its way to the front inlet ports 18, (3) The rod is hollow and serves as a means for securing a special cooling system for the pistons as was described, and (4) The rod serves as a means of support for the 25 swirl vanes 30 and 31.

Discussion of crosshead

An object is to make the engine as compact as practicable even though it employs a crosshead and crosshead 30 guide. Therefore, the back edge of the crosshead 6 is made to overlap the front end of the sleeve liner 16 by distance A (FIGS. I and II). Also the threaded boss 60 and nut 61 are permitted to project inside the sleeve-liner 16 when at top dead center. The crosshead is provided with a circular groove 29 which as shown is a smooth semitoroidal shaped contour. This permits smooth 35 unrestricted flow of the scavenge air around the front end of the sleeve-liner 16. The crosshead has sufficient length C (FIG. II) so as to resist cocking and give good 40 riding in the bore 5. Also, an adequate connection for the rod 20 is provided. It is thus seen that the above desirable features are incorporated in the crosshead shown and at the same time the engine is relatively compact due to the overlap effect A.

The crosshead may be provided with one or more seal 45 rings 62 for the purpose of retaining oil in the crankcase and also to prevent the passage or leakage of scavenge air into the crankcase.

Frame top and crosshead guide

In large engines, it is common practice to make the frame in two pieces which are generally called the main frame (or bed plate) and the frame top. The two pieces are generally bolted together at a joint located above the 55 axis of the crankshaft. This makes a rigid construction, permits easy machining of bearing pedestals, and permits the heavy crankshaft to be installed from the top without having to turn the main frame over. A feature of this invention is that the frame top 4 also serves as a crosshead guide and thereby saves the need of extra parts. A third function of the frame top is the cast in manifold 60 passage 38 for conducting and distributing scavenge air to multiple cylinders. This reduces cost and improves the appearance of the engine.

While the preferred embodiments of the invention have been described, it will be understood that the invention is not limited thereto since it may be otherwise embodied within the scope of the following claims.

What is claimed is:

1. In a double acting two stroke cycle internal combustion engine, the combination of a crankcase, a crosshead guide fastened to said crankcase, a working cylinder, a front cylinder head and a back cylinder head fastened to said working cylinder, said cylinder heads having reduced diameter bores therein, said working cylinder and

said cylinder heads being fastened to said crosshead guide, a crankshaft rotatably mounted in said crankcase, a crosshead reciprocable in said crosshead guide, a connecting rod interconnecting said crosshead and said crankshaft for respective reciprocating and rotary motion, a double acting working piston reciprocable in said working cylinder, a front valve piston and a back valve piston, each valve piston being attached to said working piston so as to form a reciprocating piston assembly, said valve pistons being reciprocable in the bores of their respective cylinder heads, a scavenge pump for supplying scavenge air, each valve piston being adapted to admit scavenge air into the interior of said working cylinder, said working cylinder having exhaust ports located in its wall, said working piston being adapted to control said exhaust ports, said piston assembly being connected to said crosshead for reciprocative motion, said piston assembly having a hollow interior, means for supplying and conducting oil to and from the hollow interior of said piston assembly so as to internally cool the piston assembly, said means for conducting oil from the hollow piston assembly interior including means for maintaining a portion of air within the hollow interior of said piston assembly so as to obtain a shaking action serving to provide good circulation and distribution of the oil inside the piston assembly, and means for regulating the volume of oil in proportion to the volume of air inside the hollow piston assembly.

2. The combination recited in claim 1 wherein the said means for regulating the volume of oil in proportion to the volume of air inside the hollow piston assembly is accomplished as follows: (a) The reciprocating motion of the piston assembly and the effect of inertia causes the oil inside the piston assembly to be thrown back and forth from one end of the hollow piston assembly to the other, (b) As the piston assembly approaches one end of its reciprocative stroke, inertia causes the oil to be thrown momentarily to one end of the hollow piston assembly, (c) A column of oil is momentarily collected in one end of the hollow piston assembly, (d) The acceleration of the piston assembly causes the oil to momentarily build up a static oil pressure which is in proportion to the height of said oil column, (e) Said static pressure forces oil out of the piston assembly through said means for conducting oil from the interior of said hollow piston assembly, (f) An increase in oil volume causes a higher oil column, hence a higher static oil pressure, hence faster drainage of the oil through said hole, (g) a reduction in oil volume causes a lower oil column, hence a lower static oil pressure, hence slower drainage of the oil, (h) thus the system is self regulating.

3. The combination recited in claim 1 wherein a baffle wall is located inside said working piston, said baffle wall serving to cause the oil inside the piston assembly to splash against the inside walls of the hollow working piston and thereby more effectively cool same, said baffle wall also serving to prevent an oil hammer effect due to back and forth motion of the oil inside the reciprocating piston assembly.

4. In a double acting two stroke cycle internal combustion engine, the combination of a crankcase, a crosshead guide fastened to said crankcase, a working cylinder fastened to said crosshead guide, a front cylinder head and a back cylinder head fastened to said working cylinder, said front cylinder head having a cylindrical bore therein, said crosshead guide having a cylindrical bore therein, a crosshead reciprocable in the bore of said crosshead guide, a crankshaft rotatably mounted in said crankcase, a connecting rod interconnecting said crosshead and said crankshaft for respective reciprocating and rotary motion, a double acting working piston reciprocable in said working cylinder, a valve piston reciprocable in said bore in the front cylinder head, said valve piston being smaller in diameter than said working piston, said valve piston being smaller in diameter than said crosshead, said valve piston being fastened to said work-

ing piston so as to form a reciprocating piston assembly, said piston assembly being connected for reciprocative motion to said crosshead, said working cylinder having within it a front working chamber and a back working chamber, a separate scavenge pump for supplying scavenge air, said valve piston being adapted to admit scavenge air into said front working chamber, said working cylinder having exhaust ports controlled by said working piston, said front working chamber having a uniflow type scavenging operation exhausting through said exhaust ports, means for porting and scavenging said back working chamber, said crosshead having a circular cross section, a seal ring adapted to serve as a sliding seal between said crosshead and said bore in the crosshead guide, means for supplying lube oil to said crankshaft and connecting rod, said crosshead and seal ring serving to prevent the escape of said lube oil from the interior of the crankcase, passage and conduit means for conducting scavenge air from said scavenge pump to said bore in the front cylinder head, the bore in said front cylinder head serving to conduct the scavenge air to the interior of said front working chamber, and said crosshead and seal ring serving to prevent passage of scavenge air through the bore of said crosshead guide into the interior of said crankcase.

5. In a double acting two stroke cycle internal combustion engine, the combination of a crankcase, a crosshead guide fastened to said crankcase, a working cylinder, a front cylinder head and a back cylinder head fastened to said working cylinder, said working cylinder and said cylinder heads being fastened to said crosshead guide, a crosshead reciprocable in said crosshead guide, a crankshaft rotatably mounted in said crankcase, a connecting rod for converting the reciprocating motion of said crosshead to the rotary motion of said crankshaft, a double acting working piston reciprocable in said working cylinder, a valve piston smaller in diameter than said working piston, said valve piston being attached to said working piston so as to form a reciprocating piston assembly, said front cylinder head having a bore therein smaller in diameter than said working cylinder, said valve piston being reciprocable in said bore in the front cylinder head, said working cylinder having within it a front working chamber and a back working chamber, a separate scavenge pump for supplying scavenge air, said valve piston being adapted to admit scavenge air into said front working chamber, said working cylinder having exhaust ports located in its wall, said working piston being adapted to control said exhaust ports, said front working chamber having a uniflow type scavenging operation exhausting through said exhaust ports, means for porting and scavenging said back working chamber, a piston rod interconnecting said piston assembly and said crosshead for reciprocative motion, said piston rod being smaller in cross section than the diameter of said valve piston, said piston rod passing inside said bore in the front cylinder head, a sleeve fastened to said front cylinder head, said sleeve projecting from the front end of said front cylinder head towards said crosshead, said valve piston being reciprocable within said sleeve, said valve piston being smaller in diameter than said crosshead, said crosshead having a groove formed in its back end, said groove serving as a clearance space for the front end of said sleeve when the crosshead is at the top dead center position of its reciprocative stroke, the back edge of said crosshead overlapping the front end of said sleeve when the crosshead is at the top dead center position of its reciprocative stroke, means for conducting scavenge air from said scavenge pump to the back interior of said crosshead guide, said groove in the crosshead being adapted to conduct the flow of scavenge air around the front end of said sleeve to the interior of the sleeve, and the interior of said sleeve serving to conduct the scavenge air on its way to said front working chamber.

6. Reciprocating parts for use in a double acting two

stroke cycle internal combustion engine comprising a working piston, a first valve piston and a second valve piston, said valve pistons being smaller in diameter than said working piston, said valve pistons being fastened one on each end of said working piston so as to form a reciprocating piston assembly, said valve pistons and said working piston being integrally cast together, said piston assembly having a hollow interior, said two valve pistons having open ends so as to provide support for a core when doing the casting job, a piston rod passing through said hollow interior, said piston rod and its appurtenances serving to close said open ends of the valve pistons, said piston rod serving to clamp said piston assembly in compression, said piston assembly being subjected to compression loads due to the clamping action of said piston rod and also due to combustion gas pressure forces acting alternately against each annular face of the working piston, said working piston having radially directed ribs located within its hollow interior, and said ribs serving to transmit said compression loads along the piston assembly so as to prevent structural failure of the working piston, said piston rod being hollow along at least part of its length, said hollow piston rod serving to conduct liquid coolant into the hollow interior of said piston assembly, and aperture means for conducting the liquid coolant back out of the piston assembly, said aperture means being in communication with ambient air whereby said hollow interior of the piston assembly is allowed to fill partly with liquid coolant and partly with air so as to obtain a shaking action of the liquid coolant inside the piston assembly, and said shaking action serving to provide good distribution of the liquid coolant inside the piston assembly.

7. Reciprocating parts for use in a double acting two stroke cycle internal combustion engine comprising a working piston, two valve pistons, said valve pistons being smaller in diameter than said working piston, said valve pistons being fastened one on each end of said working piston so as to form a reciprocating piston assembly, said piston assembly having a hollow interior, a piston rod passing through said hollow interior, said piston rod being attached to said piston assembly, said piston rod being hollow along at least part of its length, a tube located inside the hollow piston rod, said tube and the hollow portion of said piston rod serving to conduct liquid coolant to and from said piston assembly, said hollow piston rod having holes passing through its wall and opening into the hollow interior of the piston assembly for the flow of said liquid coolant, the hollow interior of said piston assembly being filled partly with liquid coolant and partly with air during operation of said engine so as to obtain a shaking action of the liquid coolant inside the piston assembly, and said shaking action serving to provide good distribution of the liquid coolant inside the piston assembly.

8. The combination recited in claim 7 wherein at least one of said holes in the piston rod serves as an orifice for

controlling the rate of flow of liquid coolant leaving the piston assembly so as to maintain a proportion of both liquid coolant and air inside the hollow interior of the piston assembly.

- 5 9. In a double acting two stroke cycle internal combustion engine, the combination of a crankcase, a crosshead guide fastened to said crankcase, a working cylinder, a front cylinder head and a back cylinder head fastened to said working cylinder, said cylinder heads having reduced diameter bores therein, said working cylinder and said cylinder heads being fastened to said crosshead guide, a crankshaft rotatably mounted in said crankcase, a crosshead reciprocable in said crosshead guide, a connecting rod interconnecting said crosshead and said crankshaft for respective reciprocating and rotary motion, a double acting working piston reciprocable in said working cylinder, a front valve piston and a back valve piston attached to said working piston so as to form a reciprocating piston assembly, said valve pistons being reciprocable in the bores of their respective cylinder heads, a separate scavenging pump for supplying scavenging air, said cylinder heads having inlet ports interrupting the walls of said bores therein, each valve piston being adapted to uncover a respective said inlet port so as to admit scavenging air into the interior of said working cylinder, each valve piston having a groove in its outer cylindrical surface, an expanding type seal ring mounted in each of said grooves, said working cylinder having exhaust ports controlled by said working piston, said working cylinder having uniflow type scavenging operations exhausting through said exhaust ports, a piston rod interconnecting said piston assembly and said crosshead for reciprocative motion, said piston rod being smaller in cross section than the diameter of said front valve piston, swirl vanes surrounding said piston rod and reciprocable therewith, and said swirl vanes serving to impart a rotational velocity to the scavenging air prior to passage of the air through said front inlet ports.
